RELIEF PRINTING MACHINE

Amos Holmes, Arthur Harold Holmes, Fred Holmes, and Amos Leslie Holmes, Birmingham, England

Application May 29, 1933, Serial No. 673,550
In Great Britain March 2, 1932

11 Claims. (Cl. 101—162)

This invention relates to relief printing machines wherein dies or engraved plates are used in conjunction with means for effecting the required pressure for printing and embossing in relief.

Hitherto printing and embossing in relief has been generally done in presses wherein the impression is obtained by a rising and falling plunger, operated by means adapted to produce the required pressure, and presses or machines of the aforesaid kind have necessarily been of heavy and massive construction in order to effect the required pressure which is simultaneously distributed over the whole surface of the die plate.

15 The object of the present invention is to provide an improved construction and arrangement of relief printing machine which is lighter in construction than the usual type of presses hitherto used and is therefore less costly to produce, and is also adapted to provide for increased speed of production.

According to the present invention we provide a machine for printing and embossing in relief, characterized by the provision and use of a vertical or upwardly inclined reciprocating die bed on which is mounted a die plate, operating in conjunction with a rotatable force cylinder adapted to give the impression and arranged to carry the sheet of paper to be printed and em-

30 bosSED over the face of the die plate during the reciprocating movement of the die bed in one direction, whereby a line pressure is made between the reciprocating die plate and the rotary force cylinder commencing at one end of the die plate and gradually extending to the other end thereof.

The invention also consists in the provision of means for inking and wiping the die plate during its reciprocating movement.

40 The invention further consists in the provision of means whereby the force cylinder is held and prevented from rotating during the reciprocating movement of the die bed when the die plate is being inked and wiped, and in means whereby an initial rotary movement is imparted to the force cylinder at the commencement of the movement of the die bed, which effects the printing and embossing operation.

The invention also consists in the provision of means whereby the pressure between the contact face of the force cylinder and the reciprocating die plate can be readily adjusted or controlled.

The invention further consists in the provision of means whereby a band of wiping paper or oth-

er material from a continuous roll is intermittently and adjustably fed over a wiper plate and moved into contact with the reciprocating die plate, the said means including mechanism for regulating the amount of wiping paper used in each operation.

The invention further consists in the provision of check mechanism whereby the rotary force cylinder can be prevented from rotation and held in a position clear of the die plate during the reciprocating movement of the latter when for any reason it is desired to temporarily discontinue feeding sheets into the machine.

The invention further consists in the provision of mechanism arranged to operate in conjunction with the check mechanism, and adapted to make inoperative the inking and the drawing through of the wiping paper, when the check mechanism is put into operation for preventing rotation of the force cylinder.

In the accompanying drawings, Figures 1, 2, and 3 are respectively a side elevation, a front view, and an opposite side elevation of a relief printing machine, constructed in accordance with and embodying the features of this invention.

Figure 4 is a diagrammatic view, on an enlarged scale, of the mechanism adapted to impart an initial turning movement to the rotary force cylinder.

Figure 5 is a diagrammatic view, on an enlarged scale, of the wiping plate and the mechanisms for adjusting and actuating same.

Figure 6 is a sectional view taken on a plane extending centrally and longitudinally through the force cylinder of the machine.

Figure 7 is a sectional view taken on a plane extending centrally and transversely through the force cylinder.

According to one practical embodiment as illustrated in the drawings, we provide a die bed 1 which is slidably mounted in vertical or upwardly inclined guides 2 fixed to the side members of the frame, and is adapted to have mounted thereon a flat die plate 3. The said die bed 1 has fitted at the front and near the sides thereof toothed racks 4 arranged to engage with pinions 5 on the ends of a cylinder 6 mounted on a shaft which is carried in the side members of the frame, the said cylinder 6 having adjustably mounted thereon a segmental pressure or force plate 105, and gripper mechanism 7 for engagement with the sheets to be printed and embossed. The adjustment of the force plate 105 on the cylinder 6 in one convenient arrangement, as seen in Figures 6 and 7, is effected by a longitudinally slidable wedge 106, mounted

75

80

85

90

95

100

105

110

in grooves 107 formed on the cylinder 6 and arranged to engage with a correspondingly inclined face on the underside of the force plate 105. Longitudinal movement is imparted to the said 5 wedge 106 by means of pinion 108 engaging with a rack 109 fixed to the wedge 106. The pinion 108 is adapted to be rotated by a worm 110 on a shaft 111, which is rotatably mounted in the fixed shaft of the cylinder 6 in which it is longitudinally 10 confined by a fixed collar 112. The shaft 111 is provided with a hand wheel 113 for the rotation of same to effect the radial adjustment of the force plate for the purpose of building up and maintaining the required pressure between the 15 force plate and the reciprocating die plate 3. The force plate 105 is mounted upon the cylinder 6 by means of bolts 114 provided with springs 115 adapted to draw the force plate to its inward position. The outer face of the force plate 105 is in 20 known manner built up with one or more layers of millboard 116 and an outer layer of force cloth 117. On the rear side of the reciprocating die bed or slide 1 are mounted toothed racks 8, preferably two, arranged to engage with toothed 25 pinions 9 fixed to a shaft 10 and adapted to have imparted thereto a reciprocating movement, the said pinions 9 being further arranged to engage with toothed racks 11 fixed on or between the side members of the frame, whereby the reciprocating movement of the said shaft 10 through 30 the pinions 9 is adapted to impart a reciprocating movement to the die bed or slide 1, which is equal to twice that of the said shaft 10, the reciprocating movement of the aforesaid shaft 10 being obtained in one convenient arrangement by means 35 of a connecting rod 12 between the shaft 10 and a crank pin 13 mounted on a pinion 14 fixed to a countershaft 15 and driven from a main or driving shaft 16. On the reciprocating shaft 10 is 40 mounted a roller 17 arranged to engage with a guide plate 18 and adapted to prevent undesired pressure of the pinion 9 in its engagement with the toothed rack 8 on the reciprocating die bed or slide 1.

45 In order to balance the reciprocating die bed or slide 1 we may employ balance weights 19 which are connected thereto by a chain or belt 20 carried over pinions or pulleys 21 mounted in the side members of the frame.

50 Between the side members of the frame and in alignment with the force cylinder 6 is mounted a transverse block or frame 22 which is adapted to support the reciprocating die bed or slide 1 and withstand the forces imparted thereto in its travel between the said block and the force cylinder in 55 the operation of printing and embossing, and in order to reduce friction between the said members, we provide any suitable form of anti-friction device which in one form may comprise vertical ribs 23 formed on the face of the fixed block 22 arranged to engage with anti-friction rollers or 60 bearings 24 interposed between the said ribs and suitable faces formed on the rear part of the reciprocating die bed or slide 1.

65 In the toothed pinions 5 of the force cylinder 6 which engage with the racks 4 on the reciprocating die bed or slide 1 is formed a clearance or cut-away part 25 which is arranged to permit of the racks moving upward without imparting rotary movement to the force cylinder 6, and mechanism is provided whereby an initial 70 turning movement is imparted to the force cylinder to bring the teeth of its pinions 5 into engagement with those of the racks 4 on the reciprocating die bed or slide 1 when the lat-

ter commences its downward movement, the said mechanism in one convenient arrangement, as seen in Figures 1 and 4, comprising an operating lever 26 having at its upper end a suitably shaped gap 27 which is engaged by a projection 80 28 on the force cylinder 6 when the latter has been moved through nearly a complete revolution in the downward travel of the die bed or slide 1, the said operating lever 26 being connected at its lower end to one arm of a bell-crank lever 29 whose other end is provided with a cam bowl 30 engaging a cam mounted on the countershaft 15, the said cam being adapted to impart movement to the operating lever 26, whereby an initial rotary movement is imparted 85 to the force cylinder 6 which is arranged to bring the teeth of its pinions 5 beyond the gap or clearance formed thereon, into engagement with the rack teeth 4 on the die bed or slide 1, at the commencement of the downward movement of the latter.

As seen on reference to Figure 4, when the force cylinder 6 is at rest during the upward movement of the die bed 1 and its racks 4, the cam bowl 30 moves over the dwell or face *a* of 100 its cam, during which period the gapped end 27 of the operating lever 26 is in engagement with the projection 28 on the force cylinder 6. When the die bed 1 commences its downward movement, the cam bowl 30 passes over the peak *b* 105 of the cam, and an upward movement is imparted to the operating lever 26 to the position shown in dotted lines, whereby an initial rotary movement is imparted to the force cylinder 6, bringing the teeth of its pinions 5 into engagement 110 with the toothed racks 4 on the reciprocating die bed 1, and as the cam bowl 30 rides down the face *c* of the cam, during the continued movement of the racks 4 and rotary movement of the force cylinder 6, the operating lever 115 26 moves to its lower position, as shown in dotted lines, with its gapped part 27 ready for engagement with the projection 28, and as the cam bowl 30 rises up the cam to the dwell part *a* thereon, the operating lever 26 is again moved 120 to the position shown in full lines, where it remains while the rotary force cylinder is at rest during the upward movement of the reciprocating die bed 1.

The cam bowl 30 is adapted to be held in contact with its cam by the weight of the operating lever 26, but if desired, a suitable spring may also be employed for the said purpose.

The inking trough and rollers may be of any suitable known arrangement, and, as seen in Figure 1, in connection therewith we provide a composition roller 31 carried on a pivoted rocking arm 32 and adapted to be oscillated so as to move the said roller from its contact with the main inking roller 33 into contact with the die plate 3 during the downward reciprocating movement of the die bed or slide 1 when it is near the end of its downward travel, the said oscillating movement being effected by a bell-crank lever 34 connected by a rod 35 with a bell-crank lever 36 provided with a cam bowl 37 arranged to engage with a cam 38 on the countershaft 15, the said cam being formed with a depression which provides, through the lever and link mechanism, a forward movement of the inking roller 31 into contact with the die plate 3 during the appropriate part of its downward travel. If desired, inking can also be effected during the first part of the upward reciprocating movement of

the die plate by arranging an appropriate dwell of the cam bowl 37 on the cam 38.

The wiping of the die plate 3 after inking, to remove the ink from the plain face thereof, is effected by means of a slightly curved wiping plate 39 over which the wiping paper is carried, the said wiping plate 39 being arranged to have imparted thereto a combined rocking and rolling motion and is adapted to continuously bring a fresh face 10 of the wiping paper into contact with the upwardly moving die plate 3. In one convenient arrangement the wiping plate 39, as seen in Figures 1, 3, and 5, is adjustably supported in the vertical position by a rod or bar 40 which is connected at 15 its lower end to one arm of a bell-crank lever 41 pivoted to the side member of the machine, the other arm of the said bell-crank lever being engaged by a screw threaded shaft 42 which is rotatably mounted on the side member of the machine and provided with a hand wheel 43 the rotation of which is adapted to impart a raising or 20 lowering movement to the wiping plate 39, in order to adjust its position in relation to the reciprocating die plate 3 to suit various sizes or dispositions of die plates. The combined rocking and 25 rolling motion of the wiping plate 39 in one convenient arrangement, as seen in Figure 3, is effected by a cam 44 on the countershaft 15 engaging with a cam bowl on one arm of a pivoted bell-crank lever 45 whose other arm is connected by a 30 rod 46 with one arm of another pivoted bell-crank lever 47, the other arm of the latter being connected by means of a transverse rod 48 with the upper end of the wiping plate 39. A second 35 cam 49 is arranged to engage with a cam bowl on one arm 50 of a pivoted bell-crank lever, the other arm 51 of the said lever being connected by a transverse rod 52 with the lower end of the wiping 40 plate 39. The rod 46 is connected to one arm of the bell-crank lever 47 through the medium of a compression spring, which, while resisting the forces transmitted through the said lever mechanism, is also adapted to permit of the adjustment of the wiping mechanism.

In order to adjust the position of the face of the wiping plate 39 in relation to that of the die plate 3, and consequently adjust or vary the pressure between the said members we provide in conjunction with inclined bearers 53 fixed to the side members of the frame, adjustable taper wedges 54 on which are fitted pegs 55 which protrude through slots in the side members of the frame and engage with pivoted arms 56 having formed therein a radial slot 57 engaged by a clamping bolt 58 and provided with a handle or knob 59. In order to adjust the wedges 54 the clamping bolt 58 is first slackened, when by means of the handle or knob 59 the arms 56 engaging with the pegs 55 can be readily moved to raise or lower the wedges 54, which constitute a bearing for the curved bearing faces 39a formed on the ends of the wiping plate 39, thereby moving the latter slightly inward or outward in relation to the reciprocating die plate 3.

The wiping web or paper 60 which is in the form of a continuous roll 61 carried on a transverse shaft 62 is arranged, as seen in Figure 1, to pass over a feed roller 63 mounted on a transverse shaft carried in bearings in the side members of the frame, and it is then passed over the face of the wiping plate 39, the used paper being guided over a transverse roller 64 and thence on to a winding drum 65.

An intermittent feed movement is imparted to 75 the wiping paper 60, as seen in Figure 3, by means

of the bell-crank lever 66 provided on one arm with a cam bowl arranged to engage with the cam 44, which as previously described is also adapted to impart a rocking movement to the wiping plate 39, the other arm of the said bell-crank lever 66 being connected by a rod 67 with ratchet clutch mechanism on a spindle or shaft 68, on which is also mounted an intermediate gear wheel 69 which engages with gear wheels mounted on the shafts carrying the feed roller 63 and the winding drum 65. The winding drum is connected to its shaft by a friction clutch or like slipping device to permit of a partial free rotation of the said shaft without rotation of the winding drum 65, such independent free movement being adapted to vary in accordance with the increasing diameter of the roll of used paper wound on the said drum. In order to prevent slip and ensure that the feed roller 63 draws the required amount of wiping paper from the roll 61, a pressure roller 70 carried on pivoted arms 71 and controlled by springs 72 is adapted to hold the wiping paper in frictional contact with the feed roller 63, as seen in Figures 2 and 3.

In order to vary or regulate the amount of 100 wiping paper used in each cycle of operation of the machine according to the size of any particular die plate in use, means are provided for limiting the movement of the rod 67 which, as before described, is adapted to impart intermittent movement to the shaft 68, on which is mounted the gear wheel 69 engaging with the gearwheels on the shaft of the feed roller 63 and the winding roller 65, the said means, as seen in Figure 3, comprising an adjustable plate 105 73 freely carried on a transverse shaft 74 rotatably mounted on the side member of the machine, the inclined upper face of the said plate 73 being arranged to engage with a roller 75 on the joint pin which connects the said rod to the 110 cam operated bell-crank lever 66. On the said shaft 74 is also freely carried an adjusting lever 76 provided at its pivot end with a lug or projection 77 arranged to engage with a lug or projection on the adjusting plate 73, so that by a 115 turning movement of the lever 76 about the shaft 74 will vary the disposition of the upper inclined face of the adjustable plate 73 in relation to the roller 75 on the end of the reciprocating rod 67, thus varying or controlling the downward movement of the said rod, and consequently varying or controlling the movement imparted to the ratchet feed mechanism on the shaft 68. The adjusting lever 76 has formed therein a 120 radial slot engaged by a clamping pin 78 mounted in the side member of the machine, and adapted to fix the said lever in any desired position.

In order to ensure that the backward rotary movement of the force cylinder 6 is arrested when the cut-away part of the teeth of the pinions 5 135 on the ends thereof reaches the position in front and out of engagement with the rack teeth 4 on the reciprocating die bed or slide 1, a spring control catch 79 engages with and forms an abutment for the lug or projection 80 on the end of 140 the force cylinder 6, as seen in Figures 1 and 4, in which position the forward movement is restrained by engagement of the gapped end 27 of the operating lever 26 with the projection 28.

In order to remove and recover some of the 145 ink removed by the wiping paper 60 from the die plate 3, a scraper device 101, as seen in Figures 2 and 3, is arranged to impinge against the wiping paper as it passes over the roller 64 after being drawn over the wiping plate 39, the said 150

- scraper device being located directly above the inking trough and the main inking roller 33, as seen in Figure 1, the ink removed by the scraper falling on to the said inking roller and back to 5 the trough.
- Check mechanism is provided for preventing rotation of the force cylinder 6 when the cut-away part of its pinions 5 aligns with and is clear of the racks 4 on the reciprocating die bed or 10 slide 1, as for instance when it is desired to run the machine for making ready the inking of the die plate and adjustment of the wiping paper; also check mechanism is provided whereby the inking mechanism and the wiping paper feed can 15 be made inoperative, as for instance when it is desired to run the machine while making ready the face of the force cylinder 6 and adjusting or regulating the pressure thereof on the die plate 3 in the reciprocating die bed or slide 1.
- 20 In the arrangement illustrated the check mechanism for the force cylinder 6 is brought into operation by the pedal 81, as seen in Figures 1 and 2, and the mechanism for checking the inking and the wiping paper is operated by the pedal 25 82, as seen in Figures 2 and 3. The spring controlled pedal 83, as seen in Figures 2 and 3, is adapted to simultaneously operate each of the check mechanisms previously described.
- In a preferred arrangement the check mechanisms, as seen in Figure 3, comprise a lever 30 84 pivoted to the side member of the frame and provided near its middle with a roller 85 engaging with a cam (not shown) on the countershaft 15, the said lever having at its lower end a notched 35 part 86 which is adapted to engage with either or both of a pair of forks 87 which are normally held clear of engagement with the said lever 84 by lugs or projections on pivoted weighted levers 88 connected by links 89 with the pedals 81 and 40 82. Upon depressing the pedal 81 a turning movement is imparted to one of the weighted levers 88, and the lug or projection on the upper end thereof is turned so as to permit of a lowering movement on one of the forks 87, thus permitting 45 it to engage with the notched end of the cam operated lever 84, and when the latter is moved outward by its roller 85 engaging with the peak of the cam, rotary movement is imparted to a tubular sleeve 90 rotatably mounted on the shaft 74 by 50 means of an arm 91 fixed on the said sleeve and hinged to the outer end of the said fork 87, as seen in Figures 2 and 3. On the said sleeve 90, as seen in dotted lines in Figure 1, is mounted an arm 92 connected by a rod 93 with a pivoted catch 55 or lever 94 which when raised engages with the lug 80 on the rotary force cylinder 6 and checks its rotation, while simultaneously an arm or lever 95 connected to the outer end of the catch or lever 94, and engaging at its outer end with the 60 rod or lever 26, causes the latter to move outward, moving its gapped end 27 clear of engagement with the projection 28 on the rotary force cylinder 6, thus permitting of the continued up and down movement of the said rod or lever 26 during 65 the running of the machine, while the force cylinder is checked. Upon depressing the pedal 82 the other weighted lever 88 is turned and permits of the other fork 87 being lowered into a position for engagement with the notch 86 in the 70 cam operated lever 84 in a manner similar to that before described, and the said fork is connected to an arm 96, as seen in dotted lines in Figure 3, the said arm being fixed to the shaft 74 to which a part rotary movement is imparted by the cam operated lever 84 through the appropriate fork 75
87. On the outer end of the shaft 74 is fixed a boss 97 provided with a lug arranged to engage with a lug on the adjustable plate 73, whereby the latter is turned to bring the notch 98 formed in its periphery under the roller 75 on the end of the rod 67, thus holding the cam bowl on the end of the cam operated bell-crank lever 66 clear of engagement with its cam, and thereby prevent movement to the rod 67, thus checking the feed mechanism of the wiping paper, while simultaneously the inking mechanism is checked by a weighted lever 99 fixed to the shaft 74, as seen in Figure 1, the said lever being provided with a projection 100 which moves into engagement with a roller 102 on the end of the cam operated bell-crank lever 36, thereby holding the said lever clear of engagement with its cam and thus checking the inking mechanism. The spring controlled pedal 83 through lever and link mechanism is adapted, when depressed, to permit both the forks 87 to be lowered into engagement with the notched end of the cam operated lever 84, whereby the check mechanism for the rotary force cylinder and that for the inking and the feed of the wiping paper are brought into operation.
- In the process of making ready for printing, one or more layers of the millboard 116 are fixed to the outer face of the force plate 105 and the latter is gradually forced outward by the adjusting mechanism into contact with the reciprocating die plate 3, thereby causing the face of the millboard to be pressed into the engraved parts of the die plate, thus producing a raised impression on the millboard corresponding to the engraved or recessed parts of the die plate, and finally the layer of force cloth 117, which may be "American" oil cloth or the like, is fixed thereto and the operation of making ready as above is continued, and when finished the segmental face of the make-up on the force plate 105 corresponds to the pitch line of the pinions 5 on the force cylinder 6.
- The operation of the machine is as follows:— We will first assume that the machine has been run and that the die plate 3 which is inked and wiped ready for printing and embossing is at the upward end of its reciprocating movement, as shown in the drawings, and is about to commence its downward movement, and a sheet has been fed up to suitable lays in position for engagement with the grippers 7 on the force cylinder 6, and the toothed pinions 5 of the latter have just moved into engagement with the racks 4 on the reciprocating die bed or slide 1. Immediately before commencement of the rotating movement of the force cylinder 6 the grippers 7 are arranged to engage the sheet. In the downward movement of the die plate 3 the sheet is drawn between the latter and the force plate 105, which is adjustably mounted on the force cylinder 6, so that a line contact is made between the die plate and the force cylinder commencing at the lower part of the die plate 3 and gradually extending to its upper part. During the continued downward movement of the die bed or slide 1, after printing and embossing the sheet, the inking roller 31 is arranged to contact with the face of the die plate 3, and wiping is subsequently effected on the upward movement of the die plate. When the die bed or slide 1 has reached the end of its downward reciprocating movement, the force cylinder 6 has been rotated nearly one complete revolution, bringing its stud or projection 28 into engagement with the slot or gap 27 in the operating lever 26 which is adapted to effect the next initial 100
- 105 110 115 120 125 130 135 140 145 150

- starting movement, and the gap or cut-away part in the toothed pinions 5 on the force cylinder 6 assumes a position clear of the racks 4. At this stage the printed sheet is released from the grippers 7 on the force cylinder 6 and may be picked up by suction or other suitable means on to the ends of delivery arms 104 adapted to be rocked by suitable lever and link mechanism actuated by a crank on the countershaft 15, the delivery arms being arranged to carry and drop the printed sheet on to endless delivery tapes 103 from which they are collected and placed on to trays for drying in the usual manner employed in connection with relief printing.
- 5 10 15 20 25 30 35 40 45 50 55 60 65 70 75
- 10 In the upward reciprocating movement of the die plate 3 the force cylinder 6 remains at rest until the die bed or slide 1 reaches the upward end of its travel and commences its downward movement, when the operating arm or lever 26 imparts an initial movement to the force cylinder 6 which brings its toothed pinions 5 into engagement with the racks 4 on the reciprocating die bed or slide 1, and the operation as before described is repeated. In relief printing a slow drying varnish ink is used on a non-absorbent paper, and great pressure is applied to the paper in its travel over the face of the moving die plate by the adjustable pressure plate 105 of the force cylinder 6.
- Having thus described our invention, what we claim as new and desire to secure by Letters Patent is:—
1. In a machine for printing and embossing in relief, a substantially vertical, reciprocating die bed, means for reciprocating said die bed, a die plate carried by said die bed, a force cylinder cooperating with said die plate, means for rotating said cylinder in one direction comprising pinions on said cylinder and racks on said die bed engaging said pinions, said pinions each having a cut-away part adapted to align with said racks when said die bed reaches the end of its movement in one direction, means for supporting a roll of wiping web, a wiping plate below said cylinder, means for feeding said web over said wiping plate, means operable to impart a combined rocking and rolling motion to said wiping plate, a lug or projection on an end of said cylinder, a spring controlled catch adapted to engage said lug when the cut-away parts of said pinions align with said racks to hold said cylinder against backward rotation only, and means for imparting an initial forward rotation to said cylinder to engage said pinions with said racks during the movement of said die bed in the opposite direction.
2. In a machine for printing and embossing in relief, a substantially vertical, reciprocating die bed, means for reciprocating said die bed, a die plate carried by said die bed, a force cylinder cooperating with said die plate, means for rotating said cylinder, means for inking said die plate, a wiping plate curved in a vertical plane having its axis of movement between and spaced from the upper and lower ends of the wiping plate, means supporting said wiping plate for rolling movement over the face of said die plate during the movement of said die bed in one direction, means for imparting rolling movement to said wiping plate, means for supporting a roll of wiping web, and means for intermittently drawing said wiping web over the face of said wiping plate.
3. In a machine for printing and embossing in relief, a substantially vertical, reciprocating die bed, means for reciprocating said die bed, a die plate carried by said die bed, a force cylinder co- operating with said die plate, means for rotating said cylinder, means for inking said die plate, a wiping plate curved in a vertical plane having its axis of movement between and spaced from the upper and lower ends of the wiping plate, means supporting said wiping plate for rolling movement over the face of said die plate during the movement of said die bed in one direction, means for imparting rolling movement to said wiping plate, means for supporting a roll of wiping web, and means for intermittently drawing said wiping web over the face of said wiping plate.
4. In a machine for printing and embossing in relief according to claim 3, pivoted arms having said taper wedges connected thereto, said arms providing means for adjusting said wedges with relation to said bearers, and means for releasably securing said arms against movement to hold said wedges in adjusted position.
5. In a machine for printing and embossing in relief according to claim 2, wherein the supporting means for the wiping plate comprises a bell-crank lever pivoted to the frame of the machine, a link supporting said wiping plate from one arm of said bell-crank lever, and a screw engaged with the other arm of said bell-crank lever and rotatably mounted on the frame of the machine, said screw being adapted when rotated to effect adjustment of the position of said wiping plate vertically with relation to said die plate.
6. In a machine for printing and embossing in relief, a substantially vertical, reciprocating die bed, means for reciprocating said die bed, a die plate carried by said die bed, a force cylinder cooperating with said die plate, means for inking said die plate, a wiping plate cooperating with said die plate, means for supporting a roll of wiping web to be drawn over the face of said wiping plate, a winding drum for said web having a gear wheel, a feed roller to contact with said web having a gear wheel, an intermediate gear wheel engaging said other gear wheels, ratchet mechanism associated with said intermediate gear wheel, a pivoted lever, a rod connecting said lever and ratchet mechanism, a rotating cam for rocking said lever in one direction to effect an intermittent rotation of said intermediate gear wheel through said rod and ratchet mechanism, said lever moving automatically in the opposite direction after each operation thereof by said cam, and means for varying the movement of said lever in said opposite direction to control the extent of movement of said intermediate gear wheel.
7. In a machine for printing and embossing in relief, a reciprocating die bed, means for reciprocating said die bed, a die plate carried by said die bed, a force cylinder cooperating with said die plate, means for rotating said cylinder in one direction comprising pinions on said cylinder and racks on said die bed engaging said pinions, said pinions each having a cut-away part adapted to align with said racks when said die bed reaches the end of its movement in one direction, means for imparting an initial rotary movement to said cylinder during the movement of said die bed in the opposite direction, a lug on an end of said

cylinder, a lever pivoted to the frame of the machine adapted to be moved into engagement with said lug when the cut-away parts of said pinions align with said racks, said lever when engaged with said lug holding said cylinder against rotation during the running of the machine, means adapted to be operated by said lever during the movement of said lever into engagement with said lug to render inoperative said means for imparting initial rotary movement to said cylinder, and treadle controlled means for moving said lever into engagement with said lug to check the rotation of said cylinder during the running of the machine.

15 8. In a machine for printing and embossing in relief, a reciprocating die bed, means for reciprocating said die bed, a die plate carried by said die bed, a force cylinder cooperating with said die plate, means for rotating said cylinder, an inking roller, means supporting said inking roller for movement into and out of operative position with relation to said die plate, means for operating said inking roller supporting means including a lever and a rotating cam for operating said lever, a wiping plate cooperating with said die plate, means for supporting a roll of wiping web, means for moving said wiping web over the face of said wiping plate including a lever and a rotating cam for operating said lever, and means by which said levers can be held clear of their cams to check the operation of said inking roller and said paper-moving means during the running of the machine.

35 9. In a machine for printing and embossing in relief, a reciprocating die bed, means for reciprocating said die bed, a die plate carried by said die bed, a force cylinder cooperating with said die plate, means for rotating said cylinder in one direction comprising pinions on said cylinder and racks on said die bed engaging said pinions, said pinions each having a cut-away part adapted to align with said racks when said die bed reaches the end of its movement in one direction, means for imparting an initial rotary movement to said cylinder during the movement of said die bed in the opposite direction, a lug on an end of said cylinder, a lever pivoted to the frame of the machine adapted to be moved into engagement with said lug when the cut-away parts of said pinions align with said racks, said lever when engaged with said lug holding said cylinder against rotation during the running of the machine, means adapted to be operated by said lever during the

movement of said lever into engagement with said lug to render inoperative said means for imparting initial rotary movement to said cylinder, an inking roller, means supporting said inking roller for movement into and out of operative position with relation to said die plate, means for operating said inking roller supporting means including a lever and a rotating cam for operating said lever, a wiping plate cooperating with said die plate, means for supporting a roll of wiping web, means for moving said wiping web over the face of said wiping plate including a lever and a cam for operating said lever, and means by which said first lever can be moved into engagement with said lug and said other levers held clear of their cams to check the operation of said cylinder, inking roller and paper-moving means during the running of the machine.

80 10. In a machine for printing and embossing in relief, a substantially vertical, reciprocating die bed, a die plate carried by said die bed, a force cylinder cooperating with said die plate, means for rotating said cylinder, racks secured to the frame of the machine, racks secured to said die bed, a shaft arranged between said first and second racks, means for reciprocating said shaft, pinions mounted on said shaft and engaging said first and second racks, a guide plate secured to the frame of the machine between said die bed and shaft, and a roller mounted on said shaft and contacting with said guide plate, said guide plate and roller preventing undesired pressure of said pinions on the racks on said die bed.

90 11. In a machine for printing and embossing in relief, substantially vertical, opposed guides, a die bed mounted for reciprocation in said guides and provided at its rear side with substantially vertical ribs, means for reciprocating said die bed, a die plate carried by said die bed, a force cylinder, a segmental pressure plate carried by said cylinder cooperating with said die plate, said pressure plate being adjustable on said cylinder so that the pressure between said pressure plate and die plate can be adjusted or controlled, a pressure block located rearwardly of said die bed and provided at its front side with substantially vertical ribs, anti-friction bearings interposed between said ribs on said pressure block and die bed, and means for rotating said cylinder.
